UNITED STATES PATENT OFFICE.

MARTIN MEYER, OF OMAHA, NEBRASKA.

DESIGN FOR A SMOOTHING-IRON.

41,974.

Specification for Design.

Patented Dec. 12, 1911.

Application filed August 24, 1911. Serial No. 645,853. Term of patent 14 years.

To all whom it may concern:

Be it known that I, MARTIN MEYER, a citizen of the United States, residing at Omaha, in the county of Douglas and State of Nebraska, have invented a new, original, and ornamental Design for a Smoothing-Iron, of which the following is a specification, reference being had to the accompanying drawing, forming a part thereof.

Figure 1 is a side view of a smoothing iron, showing my new design. Fig. 2 shows

an end view of the head of the smoothing iron.

I claim:

The ornamental design for a smoothing iron, as shown.

In testimony whereof I have affixed my signature in presence of two witnesses.

MARTIN MEYER.

Witnesses:

HIRAM A. STURGES,
